FRAMES OF SPECTACLES AND THE LIKE

Ferdinand Birkenstein, Frankfort-on-the-Main,
GermanyApplication April 25, 1936, Serial No. 76,424. In
Germany May 16, 1935

4 Claims. (Cl. 88—52)

The present invention relates to side arms for the frames of spectacles and the like which are made of any suitable material.

Side arms for spectacles are known, the crooked end portion of which press against the side of the face of the wearer of the spectacles by means of a hinge and a spring provided therein in order to obtain a secure fitting of the frame.

In accordance with the present invention these side parts of the spectacles are considerably simplified so that various parts hitherto considered essential, can be eliminated as for instance spiral springs, which are very sensitive and easily damaged, the casing for the spiral springs, bayonet-type fittings and similar expensive parts. These complicated parts frequently cause trouble in the mechanism which is often subjected to wrong and improper treatment.

The side part of the spectacles, in accordance with the invention, consists of two parts which may be moved independently to each other and which are connected together by means of freely movable metallic wire-like members passing through both parts of the side arm. A certain amount of tension provided by the metallic wire presses the curved or crooked end of the side arm of the spectacle against the side of the face.

As regards known constructions of side arms for spectacles embodying metallic wires for strengthening and stiffening the frame, the construction of the side arm in accordance with the present invention differs chiefly therein that a metallic wire is provided which latter has a bending effect. The present invention is further characterized in that the metallic wire can move freely in the main part of the side arm of the spectacles.

In order that the present invention may be clearly understood and readily carried into effect, I will describe said invention in reference to the accompanying drawing, in which:

Figure 1 shows a diagrammatical view of the construction; Fig. 2 shows an enlarged longitudinal section of a practical construction of the improved side arm; Fig. 3 is a section taken on the line III—III of Fig. 2; Fig. 4 shows a modified construction.

The curved end 1 of the side arm of the spectacles is connected in a freely movable manner to the straight portion 2 of the side arm by means of a metallic wire 4, a space 3 being left between the two parts of the side arm. The metallic wire which can be turned freely in the side arm is held fast in both parts of the side arm at its outer ends 5, by means for instance of a hook. In

order not to weaken the side arm of the spectacles at the connecting part 3, such as a collar, ball and socket joint or the like, a sleeve 6 is, for example embodied, as shown in the drawing, which engages in both ends of the two movable parts 1 and 2 of the side arm in such a manner that one of the ends is freely movable whereby the rigid side part is not weakened at the connection with the curved end. 5

A practical form of construction of such a side arm for spectacles (Fig. 2) which can be built up in the actual process of manufacture in simple manner. The metallic wire 4 connecting the curved end 1 and the straight portion 2 of the side arm is freely movable in the outer protecting casing 6 and 7 and held fast in said casing at 5 by being bent round, pressed together, soldered or otherwise. The protecting case may be covered partly or wholly. In order to obtain a clean connection between the curved end and the straight portion a metallic member 9 is provided in which rests, freely movable, the metallic head 10. In order to limit the movement of the curved end an abutment is provided which, by way of example, is represented by a nose or projection 8 which, in the drawing, has a protecting casing 7, a segment striking against said projection 8. 10 15 20 25

The segment is formed by removing a part of the surface of the sleeve 6. This sleeve is surrounded by a second protecting casing on which 30 the nose or projection 8 is formed or filled. The casing 7 is enclosed in the outer casing 2.

In the constructional form shown at Fig. 4, by way of example, the casing for the curved end 1 can be exchanged, the metallic wire 4 being provided with screw threads 11 to receive a screw threaded member 12 which, when screwed up keeps the casing in the desired position. Fig. 4 shows the end portion of a side arm in accordance with Figs. 1 and 2 but not yet bent. 35 40

It will be understood that the details may be modified without exceeding the scope of the present invention. For instance, the connecting wire may consist of several strands of wire twisted or spun together. 45

I claim:

1. A side arm for spectacles comprising a stationary part having a longitudinal bore therein, a movable curved part also having a longitudinal bore therein, said curved part being adapted to fit behind the ear, and a resilient wire connecting said parts, freely mounted in said bores, one end of said wire being fastened to the stationary part and the other to the movable part, said parts and the wire being co-axially 50 55

mounted, the connections of the wire and the side arms being remote from the junction between said parts, the outer part of the side arm being rotatable only about the common axis of the parts to torsion the wire.

5 2. A side arm for spectacles comprising a stationary part, a sleeve mounted therein having a longitudinal bore, a movable curved part, another sleeve mounted therein also having a longitudinal bore, said movable curved part fitting behind the ear, and a resilient wire connecting said parts mounted co-axially in said bores, one end of said wire being connected to the stationary part, the other end of said wire being connected to the movable part, the connections between said parts and the wire ends being remote from the junction between the parts, said parts being co-axial, the outer part of the side arm being rotatable only about the common axis 10 of the parts to torsion the wire.

15 3. A side arm for spectacles comprising a stationary part having a longitudinal bore therein, a bearing member on the end of said stationary part, a movable part also having a longitudinal bore, a bearing member carried by the end of said movable curved part, said parts being co-axially mounted, the curved part fitting 20 behind the ear, a resilient wire connecting said

parts together, the bearing members contacting, said wire being coaxially mounted in said bores, one end of said wire being connected to the stationary part and the other end to the movable part, the wire ends being connected remote from the junction between the parts and the outer part being rotatable only about the common axis of the parts, the wire being torsioned for pressing the curved part against the side of the head.

5 4. A side arm for spectacles comprising a stationary part having a longitudinal bore therein, a movable curved part also, having a longitudinal bore therein and adapted to fit behind the ear, a resilient wire connecting said parts together freely mounted for the greater part of 10 its length in said bores, one end of said wire being connected to the stationary part, the other end to the movable part, and a sleeve mounted in the ends of the stationary and movable parts to strengthen the junction thereof, the connections between the parts and the wire ends being remote from the junction of said parts, said parts and the wire being co-axially mounted, the outer part being rotatable only about the common axis of the parts to put the wire under 15 tension to cause the movable curved part to 20 press against the side of the head.

25 FERDINAND BIRKENSTEIN.
